UNITED STATES PATENT OFFICE.

WILLIAM KING RICHARDSON, OF LEAVENWORTH, KANSAS.

VARIABLE LINE-SPACER FOR TYPE-WRITING MACHINES.

1,131,958.

Specification of Letters Patent. Patented Mar. 16, 1915.

Application filed October 6, 1914. Serial No. 865,316.

To all whom it may concern:

Be it known that I, WILLIAM KING RICHARDSON, a citizen of the United States, residing at 214 North Sixth street, Leavenworth, 5 in the county of Leavenworth and State of Kansas, have invented certain new and useful Improvements in Variable Line-Spacers for Type-Writing Machines, of which the following is a specification.

10 The object of this invention is to provide a construction by which the platen may be separated from the platen ratchet-wheel which forms a part of the line spacing mechanism, in order that the platen may be turned independently of the ratchet-wheel in either direction to any extent, and to lock the platen and platen ratchet-wheel positively with ease and the fewest mechanical motions to accomplish said results, and also 15 to produce a device of this character of simple construction and that may be manufactured cheaply.

In the accompanying drawings, Figure 1, is a longitudinal central vertical section of 20 that part of the platen equipped with the line-spacing mechanism, but not including the detent, which will be understood throughout this specification to be employed, and of the same general construction of detents in 25 common use. In the type of construction shown in Fig. 1, the ratchet-wheel has no recess for the reception of the dogs which form the clutch mechanism, the clutch being peripherally held against radial movement 30 by a recess or flange on the inner face of the crown plate. Fig. 2, is a longitudinal central vertical section of a modified line spacing mechanism, the distinguishing feature of this construction from that shown in Fig. 35 1, being a recess on one side of the ratchet-wheel. Fig. 3, is a longitudinal central vertical section of a line spacing mechanism shown in locked position. The construction 40 of the line spacing mechanism shown in Fig. 45 3, differs from that shown in Figs. 1 and 2, principally in the ratchet-wheel, which has an internal central recess. Fig. 4, is a front plan view of the platen head. Fig. 5, is a plan view of the platen head opposite to the 50 view shown in Fig. 4. Fig. 6, is a plan view of the ratchet-wheel and lever clutch shown in Fig. 2. Fig. 7, is a plan-view of the crown-plate of Figs. 1 and 2, showing regulating screws 20, and anchor-screws 19. Fig. 55 8, is a longitudinal central vertical cross-sec-

tion of the platen-head. Fig. 9, is a modification of a line-spacing mechanism shown in Figs. 1, 2 and 3. In this construction the platen-head has a double cam surface, and the slide-pin 11, is equipped with a flexible 60 lever-pin that extends equidistant on each side of the slide-pin for the engagement of the cam surface of the platen-head. In the form of construction shown in Fig. 9, the crown-plate does not form a journal support, a bushing 22, being mounted upon the slide-pin for that purpose.

Referring to the drawings; 1, designates a hollow cylindrical core, preferably of wood having an outer covering of rubber, and will 70 be referred to as the platen throughout this specification.

2, designates as a whole the platen-head. The platen-head 2, comprises a circular flange 3, which bears against the platen, and secured thereto, a cylindrical hub 4, which enters and snugly fits the platen core, and is provided with a bevel 5, on one-half of the inner face of the platen-head as shown in Figs. 1, 2 and 3, and on the entire inner face 80 of the platen head as shown at 5' in Fig. 9. 6, is a stop and lock shoulder having a beveled face.

The cam or beveled face 5, is provided with a stop-pin 7. 85

8, indicates a cylindrical hub on the platen-head 2, provided with a groove 9, extending across its vertical face and to a depth flush with the flanged portion 3.

10, indicates a central perforation in the 90 platen-head for the reception of a slide-pin 11.

12, is a slot milled across the inner face of member 2, and to a depth corresponding to the clearance required to remove the dogs 95 13, which seat in slot 9.

14, indicates the platen ratchet-wheel.

15, is an internal recess on the outer side of the ratchet-wheel 14, as shown in Fig. 2. 15^a, a central internal recess in the ratchet 100 wheel 14, as shown in Fig. 3, said recesses 15 and 15^a, are for the reception of the end of the dogs 13.

The slide-pin 11, has an annular groove 16, the shoulders formed by said groove operate against the ends of the dogs 13, when the ratchet wheel is desired to be locked or unlocked to the platen-head.

17, indicates a lever pin held by slide-pin 11. The slide-pin 17, as shown in Figs. 110

1. 2 and 3, is heavy and designed to be used with flexible dogs. The lever-pin shown in Fig. 9, is preferably spring-steel, and of a diameter sufficient to admit of some flexure under the stress required to operate the clutch, the dogs forming the clutch in this figure being inflexible.

5 17^a, indicates a roller for the lever-pin 17, as shown in Figs. 1, 2 and 3.

10 18, indicates a crown-plate secured to the platen-head by anchor screws 19. In Figs. 1, 2 and 3, the crown-plate 18, is provided with a hub suitable for a journal bearing.

15 20, indicates adjusting screws held by the crown-plate 18, the ends of said adjusting screws abutting the dogs 13, near the end and are for the purpose of regulating the tension required to lock the ratchet-wheel and the platen against independent rotation, 20 and to facilitate the manufacture of the apparatus.

21, indicates a twirler or thumb wheel by which the platen may be turned independently of the ratchet wheel mechanism.

25 22, indicates a bushing which forms a journal support for the end of the platen roll equipped with the line spacing mechanism.

30 Referring to the mechanism shown in Figs. 1, 2 and 3, the operation is as follows: When it is desired to move the platen by the ratchet wheel, the slide-pin 11, is pushed in and turned to the right or from the operator until the lever-pin 17, strikes the 35 stop-pin 7. As the lever-pin 17, moves over the cam or beveled face 5, it forces the shoulder 16, on the slide pin 11, against the inner ends of the dogs 13, and pushes them inwardly causing them to bind or grip the 40 ratchet wheel 14, in this position the ratchet wheel and the platen are locked against independent rotation. To unlock the platen from the ratchet wheel, the slide-pin is turned to the left, or to the operator until 45 the lever pin 17, strikes the bevel 5^a, in this position the platen and paper may be turned back line space distance for corrections by turning the slide pin in that direction, and the platen and the ratchet wheel will move 50 together as they are locked against independent rotation due to the fact that the lever pin being in contact with the beveled surface 6, exerts binding pressure upon the ratchet wheel 14, through the clutch 13, owing to the forward travel of the slide-pin. When the platen is unlocked and it is desired to bring irregular spacing to the printing point, the slide pin 11, is pulled outwardly that the lever pin may enter the 55 slot 12. In this position the platen may be turned in either direction independent of the ratchet wheel. When the desired adjustment is made the slide pin is forced back and turned to the right until the lever pin 60 17 strikes the stop pin 7; the platen is now 65

in positive contact with the ratchet wheel, and adapted for regular spacing through the mechanism of the ratchet.

What I claim as new and desire to secure by Letters Patent, is:

70 1. In a typewriting machine, the combination of a platen, a loosely mounted ratchet wheel, a lever clutch fulcrumed upon said ratchet wheel, and mechanism for moving said lever clutch including a rotary operating element.

75 2. In a typewriting machine, the combination of a platen, a loosely mounted ratchet wheel, a lever clutch engaging one side of said ratchet wheel, and means for moving said lever clutch including a rotatable slide pin.

80 3. In a typewriting machine, the combination of a platen, a loosely mounted ratchet wheel, a lever clutch that engages said ratchet wheel, a slide pin engaging said lever clutch, and means for moving said lever clutch by turning the slide pin, whereby the platen and the ratchet wheel are locked 85 against independent rotation.

90 4. In a typewriting machine, the combination of a platen, a line-space ratchet wheel adapted to be held by a detent, a platen head, a clutch carried thereby, a slide-pin, a lever pin carried by said slide pin, and means for moving said clutch by turning said slide-pin, whereby said platen is locked or unlocked to said ratchet wheel.

95 5. In a typewriting machine, the combination of a platen, a loosely mounted ratchet wheel adapted to be held by a detent, a clutch, a slide-pin, a lever pin carried by said slide-pin, a cam adapted to engage said lever pin to effect locking or unlocking of the platen to said ratchet wheel by turning 105 the slide pin.

100 6. In a typewriting machine, the combination of a platen, a loosely mounted ratchet wheel, a rotatable slide pin, a pair of lever devices that engage said ratchet wheel and said slide pin, and mechanism for locking the platen and said ratchet wheel against 110 independent rotation including said slide pin.

115 7. In a typewriting machine, the combination of a platen, a socket secured within the core thereof and carrying a slide-pin, said slide-pin provided with a recessed shoulder, a ratchet wheel carried by said socket and adapted to be held by a pawl, a clutch carried by the socket, and means for operating the clutch by turning the slide-pin.

120 8. In a typewriting machine, the combination of a platen, a platen head, a cam upon said platen-head, a loosely mounted ratchet-wheel adapted to be held by a detent, a slide pin having a shoulder, a lever pin held by said slide pin, a pair of clutching devices carried by said platen head and adapted to 125 130

be operated by the shoulder on said slide pin to grip or release said ratchet wheel, and means for turning said slide pin in either direction whereby the lever pin engages the cam upon said platen head and moves the slide pin to effect locking or unlocking the ratchet wheel to said platen-head.

9. In a typewriting machine, the combination of a platen, a loosely mounted ratchet wheel, a lever clutch fulcrumed on said ratchet wheel, means for moving said lever

clutch including a rotary operating element, and adjusting screws for said lever clutch to regulate the tension required to lock said platen and said ratchet wheel against independent rotation.

In testimony whereof I affix my signature in presence of two witnesses.

WILLIAM K. RICHARDSON.
